UNITED STATES PATENT OFFICE.

HENRY McCABE, OF DECATUR, ILLINOIS.

CORN DRIER AND TESTER.

1,152,329.

Specification of Letters Patent. Patented Aug. 31, 1915.

Application filed June 7, 1913. Serial No. 772,449.

To all whom it may concern:

Be it known that I, HENRY McCABE, a citizen of the United States, residing at Decatur, in the county of Macon and State of Illinois, have invented a new and useful 5 Corn Drier and Tester, of which the following is a specification.

This invention relates to testers for seed corn, one of its objects being to provide improved means for supporting the kernels in position where they can be maintained at desired temperature, there being racks for supporting the ears where air can circulate freely between them so as to prevent the 15 ears from molding while awaiting the completion of the test.

A further object is to provide simple means whereby the ears from which any of the tested kernels have been removed, can be 20 quickly identified.

A further object is to provide a tester of this character which is simple in construction, cheap to manufacture, and which is proof against rodents.

With the foregoing and other objects in view which will appear as the description proceeds, the invention resides in the combination and arrangement of parts and in the details of construction hereinafter 30 described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front 40 elevation of the tester. Fig. 2 is a section therethrough, on line A—B Fig. 1. Fig. 3 is a plan view of the trays for holding the kernels. Fig. 4 is a section on line C—D Fig. 2. Fig. 5 is an elevation of one side 45 of one of the trays. Fig. 6 is an elevation of one of the next adjoining sides of said tray.

Referring to the figures by characters of reference 1 designates a casing the front and 50 back of which are open while its sides are closed, and the casing is preferably provided with an open bottom across which is extended a metal fabric 2. The front and back of the casing can be provided with 55 suitable closures such as hereinafter de-

scribed. Base strips 3 or the like support the bottom of the casing out of contact with the surface on which the device is mounted. In order to prevent rodents from gnawing through the side walls of the casing, a protecting screen 4 is preferably stretched over 60 the outer faces thereof.

The top of the casing is closed, as shown at 5, and the protecting fabric 4 is extended over this top. Arranged within the casing adjacent the top thereof is a horizontal partition 6 having upstanding flanges 7 along the sides thereof, these flanges being secured to the adjacent walls of the casing so as thus to support the partition. The partition 6 and its flanges coöperate to form a 65 heat distributing pan. A central cross strip 8 is arranged within the casing and above the partition and extends up to the top 5, the bottom portion of this strip 8 being cut 70 away at its center, as shown at 9. Depending from the partition 6 and directly below the cut-away portion 9, is a housing 10 designed to support a heater 11 which can be 75 in the form of a lamp such as shown or can be of any other desired type. This housing is closed at both sides and at one end and the other end is provided with a door 12. This door is disposed directly opposite an opening 13 formed within one of the sides 80 of the casing and which is normally closed by a door 14. Thus it will be seen that access may be had readily to the heater.

Mounted on certain of the flanges 7 and between the strip 8 and the sides of casing 1 90 are water containing trays 15 and these trays, in turn, are adapted to support top trays 16. These top trays are so arranged that vapor generated from the water contained in the trays 15, will be free to escape. 95 Each tray 16 has a strip of metal fabric 17 upon the bottom thereof and this strip supports a strip 18 of cheese-cloth or other suitable fabric. Upon the strip 18 rest intersecting partitions 19 which divide the interior of the tray into separate cells. Arranged on the outer sides of the walls of each tray 16 are letters and numerals or either letters or numerals, as shown in Figs. 5 and 6, whereby every one of the cells has 100 a distinctive designation. In other words, each cell will be designated by the two characters indicating the two columns in which the cell is located. For example, a cell designated as 2B will be the cell located in the 105 110

longitudinal column designated by the numeral 2 and in the transverse column designated by the letter B.

The front and back of the casing 1 are closed above the partition 6, the front being provided with a door 20 which, when opened, permits the trays to be withdrawn from above the water trays or pans 15.

Supported within the casing between the bottom thereof and the partition 6 are transversely extending vertical racks 21 and 22, arranged in pairs. Each of these racks is made up of vertical and horizontal wires soldered or otherwise connected at their points of intersection and the two pairs of racks are located at opposite sides of the center of the casing 1. Each rack is divided into a number of spaces equal to the number of cells in one of the trays and arranged along one side of the casing are numerals similar to those on the trays while extending across the top portion of the casing are letters similar to those on the trays. The distance between the racks of each pair is such as to enable the wires composing the two racks to support ears of ordinary lengths inserted into the openings in the racks.

Guideways 23 are provided along the upper and lower portions of the front and back of the casing and receive sliding doors 24, each of which consists of a frame 25 across which is secured a metal fabric 26.

When it is desired to use the structure herein described, water is placed in the trays or pans 15 and the heating lamp 11 is lighted. Kernels are removed from one of the ears and are placed in one of the cells in a tray 16 after which the ear is placed in the racks at a point where it will be designated by characters corresponding with those designating the cell in which the kernels have been placed. Some kernels are then removed from another ear and placed in another cell and the ear is arranged properly in the rack. This course can be pursued until kernels have been placed in all of the cells in the trays and all of the openings in the racks have been filled with ears.

The trays are then placed in position above the water trays 15 and door 20 is closed. Doors 24 are also closed. The heat generated by the lamp will circulate under the trays 15 so as to cause the generation of vapor and by keeping the kernels supplied with moist hot air for several days, they will be caused to sprout.

As the ears are supported in the lower portion of the casing where air is free to circulate between them, it will be seen that they will be kept dry and thus prevented from molding.

By providing the metal fabric 17 in each tray 16 and the cloth 18 upon the metal fabric, air cells are produced under the ker-

nels supported in the trays so that the bottoms of the kernels are kept comparatively dry during the testing operation.

While in the drawings, two trays 16 and two water trays 15 have been illustrated, it is to be understood that this number may be varied at will, it being possible to use either one, two, three or more of each.

What is claimed is:—

1. The combination with a casing, an ear supporting rack therein having a central space adapted to extend between the supported ears and a heater suspended within said space, of a heat distributing pan extending within the upper portion of the casing and communicating with the heater, a water tray supported above said pan, a seed tray resting upon the water tray, and co-operating means upon the bottom of the seed tray for supporting kernels, said co-operating means forming air cells, there being free communication between the portions of the rack about the heater.

2. The combination with a casing, an ear supporting rack therein having a central space adapted to extend between the supported ears, and a heater suspended within said space, of a heat distributing pan extending within the upper portion of the casing and communicating with the heater, a water tray supported above said pan, a seed tray resting upon the water tray, and co-operating means upon the bottom of the seed tray for supporting kernels, said co-operating means forming air cells and including an open mesh metal fabric resting on the bottom of the seed tray, and a soft seed engaging fabric bearing on the metal fabric, there being free communication between the portions of the rack about the heater.

3. The combination with a casing, an ear supporting rack therein having a central space adapted to extend between the supported ears, and a heater suspended within said space, of a heat distributing pan extending within the upper portion of the casing and communicating with the heater, a water tray supported above said pan, a seed tray resting upon the water tray, co-operating means upon the bottom of the seed tray for supporting kernels, said co-operating means forming air cells and including an open mesh metal fabric resting on the bottom of the seed tray, a soft seed engaging fabric bearing on the metal fabric, and intersecting partitions within the seed tray and extending from said fabric upwardly to the top of the tray and dividing said tray into separate kernel receiving cells, there being free communication between the portions of the rack about the heater.

4. The combination with a casing, an ear supporting rack therein having a central space adapted to extend between the sup-

ported ears, and a heater suspended within said space, of a heat distributing pan extending within the upper portion of the casing and communicating with the heater, a water tray supported above said pan, a seed tray resting upon the water tray, coöperating means upon the bottom of the seed tray for supporting kernels, said coöperating means forming air cells and including an open 10 mesh metal fabric resting on the bottom of the seed tray, a soft seed engaging fabric bearing on the metal fabric, and intersecting partitions within the seed tray and extending from said fabric upwardly to the

top of the tray and dividing said tray into 15 separate kernel receiving cells, said seed receiving tray being slidable horizontally into and out of position above the water tray, there being free communication between the portions of the rack about the 20 heater.

In testimony that I claim the foregoing as my own, I have hereto affixed my signature in the presence of two witnesses.

HENRY McCABE.
